EXPANSION WELL PUMP

Joe H. Kidder, Los Angeles, Calif.

Application October 17, 1936, Serial No. 106,095

13 Claims. (Cl. 103—44)

My invention relates to a pump more specifically for use in deep wells such as oil wells in which the pumping action is developed by compressed air conducted downwardly to the pump through pipes provided for such purpose and in which the liquid, such as oil, to be elevated is forced upwardly preferably through oil tubes to the top of the well, such oil tubes being located within the well bore or well casing and providing a housing structure for the pump or pumps. In some cases the liquid may be forced upwardly above the pump through the well casing.

In the above mentioned type of pump an object and feature of my invention is to develop the pumping action by the expansion and contraction of a flexible medium which when contracted by a reduced air pressure, allows inflow of liquid such as oil into a pumping compartment on the exterior of the expansible medium, such medium when subject to compressed air expanding and thereby forcing the liquid outwardly, whereby through the use of check valves the liquid can only have an upward direction of flow. A more specific object and feature of my invention is in constructing the flexible medium of a rubber or similar tube securely attached to the air pipe, which pipe is perforated at the parts covered by the rubber tube. A pump structure forms a chamber for the liquid, such as oil, to be pumped, on the outside of the expansible tube and when the tube is collapsed in close contact with the air pipe through a reduction of air pressure, a considerable volume of liquid may fill this liquid chamber. However when the air pressure is increased, the rubber tube expands, thus increasing materially in diameter, and positively displaces a quantity of liquid such as oil, which is forced upwardly through non-return check valves. In this connection, to prevent undue expansion of the rubber tube, a confining cylinder, this being preferably perforated, is positioned outside of the rubber tube, the interior of this confining cylinder forming a part of the liquid or oil chamber, the outside of this chamber being defined by a cylindrical pump barrel.

Another object and feature of my invention as to one form of the pump, is in the construction and assembly of a cylindrical pump barrel having an inlet check valve at the bottom. This barrel preferably has a perforated head and is attached to the air pipe so that it may be lowered into the well, the string of air pipe being built up as the pump barrel with the assembled pump is lowered. Located inside of the pump barrel and confined by lower and upper heads which form

seats, the lower seat having perforations, is the confining cylinder, the air pipe with the perforated section and the flexible rubber tube confined thereto. The upper head has check valves for non-return flow of the oil being elevated. Therefore when the rubber tube is deflated it has a snug fit on the perforated section of the air pipe and liquid such as oil may flow upwardly through the check valve in the lower head of the pump barrel and fill the annular space between the pump barrel, the confining cylinder and through the perforations of this cylinder to the outside of the rubber tube. When the air pressure is increased this rubber tube expands laterally, the limit being the confining cylinder, and thus forces the oil inside of the confining cylinder outwardly. This pressure causes a seating of the lower check valve and opens the upper check valves for upward flow of the oil. In this type of pump it is preferable to have a packer between the oil barrel and the well casing below the perforated head so that the oil passing upwardly through this perforated head of the pump barrel flows upwardly inside of the well casing.

A detail feature of my invention resides in the manner of attaching the rubber tube at its upper and lower ends to the air pipe surrounding the perforated section. For this purpose it is preferable to have the rubber tube with upper and lower flanges or beads and engaged by upper and lower split bushings. Each bushing is threaded into a plug, there being a lower plug seating on the lower head or seat in the pump barrel, such being above the bottom head having the intake check valve and the upper head having the check valves therein for the upward flow of oil from the oil or liquid chamber. These bushings are flared on the inside to give a gradual curvature to the end portions of the expansible rubber tube so that no sharp bends accrue during the expansion and contraction of this rubber expander. The bushings are brought into contact with the confining cylinder. It is also preferable in the rubber expander to incorporate fabric at the end portions where there is but little expansion as a stiffening structure but to have the expanding section formed of resilient rubber.

Another feature of my invention provides for the blowing out of water condensation or other liquid from the air pipe. This pipe therefore at the bottom is provided with an outlet valve which incidentally prevents inflow of oil when the assembly is lowered into a well, and as the portion of the air pipe having the rubber expander thereon may be slightly elevated or unseated, the

building up of an air pressure in the air pipe will thus blow off any water condensation or other liquids.

- 5 Another feature of my invention is arranging the pump assembly so that, for instance, the air pipe with the rubber expander attached thereto by bushings may be unseated and elevated or this removable assembly may include the confining cylinder.
- 10 Another object and feature of my invention is in the provision and construction for pumping the liquid or oil from deep well pumps in stages, that is, from a bottommost pump to a pump next above and from this second pump to a still higher 15 pump is necessary so that each stage will not have too great a lift. In this construction the pump barrel for each pump has an oil tube connected thereto and extending to the pump next above. In this case the provision can be made 20 for withdrawing the upper pump assembly only and the oil tube is preferably of substantially the same diameter as the pump barrels. In this type of construction for pumping in stages, the oil tubing connected to the bottom of an upper pump 25 barrel is perforated so that the oil may flow outwardly through these perforations into the well casing above a packer. This is done as all of the pumps operate simultaneously in expansion and contraction of the rubber expander on account 30 of having a single string of air pipe extending downwardly to supply all of the pumps and thus a lower pump builds up a hydraulic head of oil in the casing surrounding the pump barrel of the pump next above on the lift or expansion stroke 35 as the intake check valves of all the pumps are simultaneously closed and then on the contraction action the oil flows from this body surrounding an upper pump into the oil chamber of such upper pump and is elevated on the next expansion 40 stroke.

It will be noted that a characteristic feature of my invention is that no air escapes into the body of liquid being elevated but that the pumping is done by the expansion and contraction of the 45 rubber expanders, the action of which is developed by increasing and decreasing the air pressure in the air pipe. Hence a further detail feature of my invention resides in the control of an air compressor or the air confined in a storage 50 tank under pressure. This is arranged so that for instance the compressor for a period of time builds up a compression in the air pipe and then for another predetermined period such air is released and may be discharged to atmosphere, 55 thus reducing the pressure. This action is automatically arranged by operation of an air valve which may be automatically connected to an air compressor or other moving mechanism. It will be appreciated that in my invention that although the expansion as to diameter of the rubber expander is somewhat limited due to the usual diameters of oil wells or the like, nevertheless these rubber tubes forming the expander 60 may be of very considerable length compared to their diameter and thus at each expansion cause the movement upward by displacement of a relatively large body of liquid. The pumping however is somewhat slow on account of the time period necessary to build up the air pressure in a long 65 string of air pipe and to release such pressure.

My invention is illustrated in connection with the accompanying drawings, in which:

Fig. 1 is a vertical section through a portion 75 of a well casing and one form of my pump taken

substantially on the line 1-1 of Figs. 2 or 3 in the direction of the arrows.

Fig. 2 is a horizontal section on the line 2-2 of Fig. 1 in the direction of the arrows omitting the casing.

Fig. 3 is a horizontal section on the line 3-3 of Fig. 1 in the direction of the arrows.

Fig. 4 is a vertical section through an assembly of pumps for multiple stage pumping from a deep well.

Fig. 5 is a diagram in elevation showing a supply and control mechanism for the compressed air.

Fig. 6 is a vertical section showing a modified form of the pump elements, this including a 15 flexible inflatable bag.

Dealing first with the construction of Figs. 1, 2 and 3, this is illustrated by a portion of a well casing 11 having a cap 12 with an outlet 13 for oil. The cap is provided with a packing and 20 packing assembly 14.

The pump proper designated by the numeral 20 has a cylindrical pump barrel 21 with a bottom head 22 secured therein in any suitable manner, this head being provided with an intake 25 check valve 23 shown as a ball valve. A lower combination head and seat 24 is secured in the pump barrel and has a series of perforations 25 or passages leading upwardly from the bottom oil compartment 26. There is an upper combination head and seat 27 having ports 28 with non-return check valves 29 allowing upflow of oil or liquid but preventing the downflow. This has an upper sloping seat 30.

A confining cylinder 35 has an upper end 36 35 fitted to the head 27 by an annular depending rib 37. The lower end 38 is secured at 39 to the lower head 24 which has an inner tapered seat member 41 and an end 42 with a plugged opening 43.

The compressed air pipe 45 extends downwardly through the cap 12 and has a sliding fit with the neck 46 of an upper head 47 of the pump barrel 21, there being a screw threaded connection 48. This upper head is shown as sloping and having 45 a series of perforations 49. A collar 50 to engage with this head is secured to the air pipe 45.

The expander assembly designated by the numeral 55 utilizes a perforated section 56 of the air pipe and over this is fitted an expandable tube 57, this being preferably formed of rubber and is illustrated as having ends 58 with a bead 59 on the end. Lower and upper split bushings 60 and 61 are used to securely clamp the beaded ends of the rubber tube to the perforated portion 56 of the compressed air pipe. The upper bushing is illustrated as screw threaded to a plug 62, which plug is attached to the compressed air pipe and seats on the seat 30 of the upper head and seat 27. A lower plug 63 is secured to the 60 lower end of the air pipe section 56 and has the lower split bushing 60 screw threaded thereon. It will be noted that these bushings have an outward flare 64 to confine the end portions of the rubber tube to a gradual expansion on an 65 easy curve. The bushings extend outwardly substantially to the confining cylinder 35.

A check valve 70 is mounted in the bottom of the lower plug 63 and has a light spring to retain the valve closed. This prevents entry of 70 oil or liquid into the air pipe 45 at the bottom when the pump is lowered into a well and also operates as a blow off valve to blow condensed water or other liquids out of the air pipe.

In the operation of the device as shown in 75

Figs. 1, 2 and 3, the pump is assembled at the top of the well and lowered in the well casing as sections are added to the compressed air pipe 45. In this action the collar 50 engages the head 49, this unseating the plugs 62 and 63 from their respective seats and the pump assembly being supported by the engagement of the collar 50 and the head 49. When the pump is at the desired depth for instance in the portion 10 of the casing for oil, a packer 71 is fitted between the pump barrel 21 and the casing 11. It thus seals off the upper part of the casing to the top of the well. The air pipe 45 with the expander assembly 55 may then be lowered until 15 the plugs 62 and 63 seat on the respective seating heads 24 and 27. As above mentioned, the check valve 70 prevents entrance of oil into the air pipe sections 56.

The assembly is now in position for pumping 20 action which is done by alternately and at a slow rate forcing compressed air downwardly through the pipe 45 until the rubber expander tube 57 is pumped outwardly, the limit of the expansion being the confining cylinder 35. This cylinder in practice is placed as close to the pump barrel 21 as possible, leaving however sufficient room for the passages or perforations 25 and 28 and the check valves 29. The oil flows in through the check valve 23, and manifestly when the 25 rubber tube expands the oil trapped in the chamber 44 can only move upwardly through the check valves 29 and thence through the perforations 49 in the head 47 and upwardly in the well casing 11. When the air pressure is reduced 30 in the air pipe 45 the rubber expander tube 57 collapses, thus allowing for an inflow of a second charge of oil through the valve 23 due to the pressure in the well. The action is then repeated.

If a liquid such as water condenses in the 35 lower part 56 of the air pipe 45, the air pipe with the assembly of plugs 62 and 63 may be lifted about a foot or so, so as to break the seal at the tapered seat 41. Air is then forced down under pressure through the pipe 45 and the lower 40 extension 56, however this does not expand the rubber tube 57 but causes the check valve 70 to open and flow any condensed liquid out of the air pipe. This only requires a slight increase of pressure over that of the oil from the well. This pressure of the well oil prevents the rubber 45 tube 57 from expanding. In this action of the short lift of the compressed air pipe 45 which unseats the plugs 62 and 63, there is no movement of the confining cylinder 35, this being rigidly held in position by the heads 24 and 37.

In view of the fact that the lower plug 63 and also the split bushing 60 have a sliding or working clearance in the perforated confining cylinder 35, it is in reality only necessary to elevate the air pipe 54 with its attached perforated 50 section 56 in order to break the tapered joint at the seat member 41. The compressed air therefore forces any condensed water or other liquid outwardly through the check valve 70 and this will rise in the confining cylinder 35 until 55 it may flow out of the lower perforations. Any liquid which is trapped below such bottom row of the perforations is forced upwardly when the lower plug 63 is again seated on the lower seat member 41.

In the construction shown in Fig. 4 I make provision for pumping in stages, that is, from a bottommost pump to one next above and so on to the top of the well. In this illustration a 60 well casing is indicated by the numeral 80. In

actual construction the casing is usually tapered from the top to the bottom of the well. In the illustration a lowermost pump 81 is shown and a pump 82 next above but it will be understood that there may be a series of these pumps. Dealing first with the construction of the lower pump 81, this has a pump barrel 83 with a standing intake valve 84 at the bottom. A combination head and seat 85 is located above the standing valve and has a seat 86 and oil passages 87. An upper combination head and seat 88 is also secured to the pump barrel and has a sloping seat 89. The perforated confining cylinder 90 is secured at its lower end to a lower plug 91, this seating on the seat surface 86 of the lower head 15 85 which may be similar to that shown in Fig. 4 and have a plug at the bottom. The plug 91 has a blow-off valve 92.

The air pipe 93 has a lower perforated section 94 and is connected at the bottom to the plug 20 91. The rubber expander 95 has beads 96 at its opposite ends and is confined by the split bushings 97 at the bottom and 98 at the top. The bushing 97 is secured to the plug 91 and the bushing 98 is shown as secured to an upper 25 plug 99. The confining tube 90 is illustrated as connected at 100 to the plug 99. This upper plug has oil ducts 101 with non-return check valves 102 at the top. It will be noted in this case that the confining tube 90, the plugs 91 30 and 99, the bushings, the perforated section 94 of the air pipe and the rubber expander tube 95 form an assembly which may be completely removed in a manner hereinunder described without disturbing the pump barrel 83. 35

A string of oil tubing 110 extends upwardly from the barrel 81 of the lower pump and if desired may be the same diameter as this barrel. A packer 111 between the upper portion of this oil tube and the well casing slightly below the upper pump 82 separates the casing into different lengths so far as the pumping of oil is concerned. Above the packer there are perforations 112 leading from the inside of the oil tube to the annular space between such tubing and 40 the casing. 45

The upper pump 82 is quite similar in design to the lower pump, having a pump barrel 115. In this case a coupling head 116 may be used for coupling the upper end of the oil tube 110 and the lower end of the pump barrel 115 or these may be coupled in any suitable manner. This head 116 functions as a lower head for the upper pump and is provided with a seat 117, oil passages 118, each having a check valve 119 and the air pipe 93 is 50 connected through the head 116. The upper head 120 is similar to the head 88 having a sloping seat 121. In this case the lower plug 122 which is provided with a compressed air passage 123 and does not have any blow-off valve, seats directly 55 on the seat 117. The confining tube 124 is connected directly to the plug 122. The perforated section 125 of the air pipe 126 is connected to the plug 122. The rubber expander tube 126 having end beads 127 is confined by a split bushing 60 128 connected to the plug 122 and the upper bushing 129 is connected to the upper plug 130 and also to the upper end 131 of the confining tube 124. The upper plug 130 is illustrated as the same as the plug 99 of the lower pump 81. The 65 oil leads upwardly above the plug 130 through an upper string of oil tubing 132 and thus leads to a succession of pumps if necessary or to the top of the well.

The operation of the multiple stage pump of 75

- Fig. 4 is substantially as follows: On account of the compressed air pipe leading downwardly through all of the pumps to the lowermost, the rubber expander tube of each of these pumps will be expanded simultaneously on increase of air pressure and likewise collapsed or contracted simultaneously on decrease of the air pressure. The oil is pumped by the lower pump upwardly through the tubing 110 and as there is an internal pressure at the same time in the upper pump 82, this oil flows outwardly through the perforations 112 into the annular space defined by the well casing, the pump barrel of the upper pump and the packer 111. On the contraction stroke or cycle, the head developed forces oil through the check valves 119 into the oil chamber of the upper pump so that on the expansion cycle of this pump such oil is forced upwardly to a third pump and so on or to the top of the well.
- In this construction the various pumps may be disassembled in a sequence from the top downwardly for removing the confining cylinder and all of the operating parts connected to the upper and lower plugs of each pump. For instance, these parts of the upper pump, if it requires repair, could be pulled upwardly with the air pipe, thus completely removing this upper assembly except the heads 116 and 120 from the pump barrel of the upper pump and the oil tubing. It can likewise be re-inserted. If it is necessary to remove the lowermost pump, the upper oil tubing with the upper pump barrel may be removed by disconnecting from the head 116 or this head may be left attached to the upper pump barrel and disconnected from the oil tubing 110. Then a connection can be made to the air pipe 93 and a lower pump assembly including the confining tube and the lower and upper plugs connected thereto removed upwardly. In this case where it is desired to blow out condensation from the lowermost pump it is necessary to first remove the upper pumps, make an air connection to the lowermost pump and slightly unseat such pump so that the blow-off valve 92 may be operative.
- In Fig. 5 I illustrate in a diagrammatic manner a suitable means for developing the pulsations of compressed air in the pump or series of pumps in a well. In this illustration an air compressor is indicated by the numeral 150 having a compressor structure 151, a rotating shaft 152 with a fly-wheel pulley or the like 153 connected thereto. The compressed air flows outwardly through a pipe 154 connected to a lead pipe 155, there being a regulating blow-off valve 156. The pipe 155 leads through a suitable valve 157 such as a two-way valve which has a connection 158 to the compressed air pipe leading to the pumps and a waste connection 159. This valve is illustrated as having a stem 160 with a lever 161 connected thereto having a roller 162 on the arm. The arm is normally retracted by a retraction spring 164. A cam 165 is mounted on a shaft 166 and this cam is shown as being driven by a belt or equivalent drive 167 from the shaft 152 or the pulley or the like 153.
- In operation of this device, the spring normally holds the valve in its open position, that is, forming a compressed air connection from the pipe 155 to the pipe 158 leading to the well, therefore the compressed air from the compressor is lead to the air pipes in order to build up a pressure in the string of compressed air pipes leading to the various pipes, thus causing expansion of the rubber expander tubes. After a predetermined period the roller 162 rides on the high part of the cam

165 which turns the valve forming a waste connection from the pipe 158 to the outlet 159 thus releasing the pressure in the pumps to atmosphere. During this period the compressor is still operating but will blow-off through the valve 156. In this type of pump of course, a considerable time period is required to build up the pressure to expand each of the pump elements and also to reduce the air pressure for the intake cycle of the pumps. It is of course necessary that the air be pumped to the lowermost pump. It is merely necessary to increase or decrease the pressure of air in each of the pumps and hence a comparatively small volume of air is all that is necessary to operate one or more pumps in a well, this of course being dependent on the length of the rubber expanders, the diameter to which they expand and the pressure in the well to be overcome in the lift.

In Fig. 6 I show a modification of the pump structure in which instead of an expandible rubber tube I employ a flexible expandible and collapsible structure similar to a bag or tube. In this illustration a pump barrel is designated by the numeral 175 having a lower head with a seat 176 and an upper head 177 also with a seat. The perforated portion of the air pipe 178 is connected to a bottom closed plug 179 and an upper valve plug 180. The flexible and to a certain extent foldable tube or bag 181 is secured at its opposite ends 182 between clamping rings 183 and 184 and held in place at its ends by flared bushings 185. The plugs are seated on the respective heads much the same as in the constructions shown in Figs. 1 and 4. In this case however I omit the perforated confining cylinder and allow the bag to expand until it contacts the pump barrel 175.

The foldable inflatable bag or tube may be made of a fabric material somewhat as employed in the manufacture of balloons only of heavier weight. This does not stretch in the manner of a rubber tube but when collapsed will fold in an irregular manner around the perforated air tube 178. Then when the compressed air is forced downwardly in the air tube the bag or flexible tube expands and in its expansion forces the oil between the tube and the pump barrel upwardly. The flared bushings support the end portions of the expandible flexible tube preventing any sharp or angular bends. The bushings are close enough to the pump barrel to prevent any pinching of the bag but still allow an upward flow of the oil as it is displaced by the bag.

Various changes may be made in the details of the construction without departing from the spirit or scope of the invention as defined by the appended claims.

I claim:

1. A pump comprising in combination a cylindrical pump barrel having an intake standing valve at the bottom, a lower and an upper head, each having a seat, the lower head having passages for liquid, an air pipe having a perforated section with a plug at the bottom forming a closure, an upper plug adapted to engage the upper seat, a resilient expandible tube mounted over the perforated section whereby on increasing of air pressure in the pipe, the said tube becomes expanded and thereby forces liquid upwardly, there being valved passages for the upward flow of liquid from the space between the tube and the pump barrel.

2. A pump as claimed in claim 1, the expandible tube being connected to the said pipe by bushings,

the upper and lower plugs with the bushings being removable through the upper head by elevating the air pipe.

3. In a deep well pump, the combination of a well casing, a lower pump having a pump barrel, an oil tube connected thereto, a packer between the upper part of said tube and the well casing, said oil tube being perforated above the packer, an upper pump having a pump barrel with an upper oil tube connecting thereto and leading upwardly in the well, the lower oil tube being connected to the upper pump, a common air pipe leading downwardly through the pumps, each pump having a perforated section of the air pipe with an expansible and collapsible flexible member connected thereto, means at each pump forming an oil chamber with inlet and outlet valves, each chamber surrounding the flexible member, the outlets for each valve communicating with the oil tube thereabove.

4. In a deep well pump as claimed in claim 3, each pump having a lower and an upper head with a seat and having lower and upper plugs connected to the perforated section of the air pipe to seat on said heads, the plugs of the upper pump with the air pipe connected thereto being first removable and then the oil tube and the pump barrel of the first pump being removable and the plugs with the air pipe of the lower pump being then removable.

5. In a deep well pump the combination of a well casing, a lower pump having a pump barrel, a lower oil tube connected thereto, an upper pump having a pump barrel with an upper oil tube connected thereto and leading upwardly in the well, means adjacent the upper oil pump to trap oil pumped upwardly by the lower pump through the lower oil tube, means connecting the lower oil tube to the upper pump, a common air pipe leading downwardly through the pumps, each pump having a perforated section of the air pipe with an expansible and collapsible flexible member connected thereto, means at each pump forming an oil chamber with inlet and outlet valves, each chamber surrounding the flexible member, the outlets for each valve communicating with the oil tube thereabove.

6. In a deep well pump as claimed in claim 5, each pump having lower and upper plugs connected to the perforated section of the air pipe with means on which said plugs seat, the plugs of the upper pump with the air pipe connected thereto being first removable and then the lower oil tube and pump barrel of the upper pump being removable and the plugs with the air pipe of the lower pump being then removable.

7. In a deep well pump the combination of a well casing, a lower pump having a pump barrel, a lower oil tube connected thereto and extending upwardly, an upper pump having a pump barrel with an upper oil tube connected thereto and leading upwardly in the well, means connecting the lower oil tube to the upper pump barrel, means surrounding the upper pump barrel and having communication with the upper portion of the lower oil tube to receive oil pumped upwardly by the lower pump, a common air pipe leading downwardly through the pumps and the pump barrels, each pump having a perforated section of the air pipe with an expansible and collapsible flexible member connected thereto, means at each pump forming an oil chamber with inlet and outlet valves, each chamber surrounding the flexible member, the outlets from each outlet

valve communicating with the oil tube thereabove.

8. In a deep well pump the combination of a tubular means to suspend a pump barrel in a well, said barrel having the standing valve at the bottom opened for flow of oil by the pressure in the formation and having check valves at the top open for upward flow of oil through the tubular structure by pressure developed between the standing and the check valves, an expansible structure positioned in the pump barrel, means forming an internal support of the expansible structure, a closure means for opposite ends of said expansible structure, an air pipe connecting from the expansible structure to the top of the well, means to produce an increase and a decrease of air pressure in the air pipe and hence expand and permit contraction of the expansible structure, means to separate the tubular supporting structure from the pressure in the well on the standing valve whereby such pressure in the well normally fills the pump barrel outside of the expansible structure between the standing and the check valves, the expansible structure on increase of air pressure in the pipe being expansible to force the oil upwardly through the check valves, the pressure of the well fluid operating by a flow through the standing valve being operative to collapse the expansible structure on decrease of air pressure whereby on periodic changes of increase and decrease of air pressure, the oil is pumped upwardly in the well.

9. In a deep well pump the combination of an oil conveying tube having a pump barrel connected thereto, the said tube extending to the top of the well, said pump barrel having a standing valve at the bottom for inflow of oil from the formation, an upper head, a plug seated on the upper head, check valves in said plug, a lower head having ports therethrough, a plug seated on the lower head, the lower plug being of less diameter than the upper plug to pass therethrough, an air pipe extending downwardly from the top of the well and connected to the upper and lower plugs and having a perforated section between the plugs, a flexible foldable collapsible and expansible tube attached to the pipe and the plugs and enclosing the perforated section, an air flow means at the top of the well to periodically increase and decrease the air pressure in the air pipe whereby on increase of pressure the flexible tube becomes expanded and thereby displaces oil trapped between the standing and the check valves upwardly through check valves and whereby on decrease of air pressure, the pressure and flow of the oil from the well through the standing valve is adapted to collapse the said foldable tube whereby the pressure of the oil from the formation fills the pump barrel between the standing and the check valves and surrounding the foldable tube, the said perforated portion of the air pipe forming a means to interiorly support the foldable tube when collapsed.

10. A pump comprising in combination a pump barrel with a standing valve in the base thereof, a compressed air pipe having a connection centrally to an expansible tube mounted on a section of the air pipe, such section being perforated, a foraminous confining cylinder held in a fixed position between the tube and the pump barrel, the space between the barrel forming a liquid chamber with an inlet at the bottom above the standing valve and an outlet at the top having a non-return valve, the said tube being adapt-

- ed to expand on internal air pressure in the perforated air pipe to force liquid in the said chamber upwardly through the outlet and the non-return valve, the pump barrel having a lower and 5 an upper head, each with a seat, the air pipe having lower and upper plugs seated thereon, the lower plug having a blow-off valve whereby on elevating the perforated air pipe the blow-off valve may operate to discharge liquid from the 10 perforated pipe.
11. In a pump, a hollow expansible structure, means to support said structure internally, the said structure having means for inflation with air from the top and means to prevent the leakage 15 of air from the lower part of said structure, means forming a liquid chamber on the outside of the expansible structure, valves for in and out flow of liquid to and from said chamber whereby on decrease of air pressure in the expansible 20 structure said structure collapses to engage the internal support and causes the liquid chamber to be filled with liquid and on inflation of the said expansible structure such structure expands and forces liquid from said chamber, the said 25 expansible structure having a flexible and foldable wall whereby when the structure is collapsed the wall may have a series of folds and when expanded the wall becomes unfolded without stretching the material forming the wall.
- 30 12. In a pump, an expansible structure having a flexible and foldable wall whereby when the structure is collapsed the wall may have a series of folds and when expanded the wall becomes un-

folded without stretching the material forming the wall, means to support the expansible structure at its upper and lower ends against movement at least for in and out flow of air, means for inflating the expansible structure with air, 5 means to prevent the escape of the air from the expansible structure, means forming a liquid chamber on the outside of the expansible structure, valves for in and out flow of the liquid to and from the chamber whereby on inflation 10 and deflation of the expansible structure, liquid is pumped through the said liquid chamber.

13. A pump comprising in combination a compressed air pipe having a section thereof with perforations and a resilient expansible tube 15 mounted over the perforated section, means forming a liquid chamber on the outside of the said tube with an inlet and outlet, each having a valve, means to increase and decrease the air pressure in the pipe whereby the tube becomes 20 inflated and deflated to expand and to again contract the tube whereby on expansion of the tube liquid is forced from the liquid chamber outwardly through the outlet, the air pipe having a plug below the lower end of the expansible tube, 25 said plug having a valve therein, a seat for said plug whereby the valve and the plug is rendered inoperative during the expansion and contraction of the tube in pumping, the said plug being adapted to be elevated on its seat whereby the 30 valve of the plug may become operative for blowing liquid out of the air pipe.
